REFINING OF SULFUR BEARING MINERAL OILS WITH DIALKYL POLYSULFIDE

Robert G. Capell, Pittsburgh, and James H. Wright, Penn Township, Allegheny County, Pa., assignors to Gulf Research & Development Company, Pittsburgh, Pa., a corporation of Delaware

No Drawing. Application August 3, 1953,
Serial No. 372,199

8 Claims. (Cl. 196—24)

This invention relates to refining of sulfur bearing mineral oils and more particularly to treatment of crude or refined mineral oils or components thereof which contain sulfur determinable as elemental sulfur, in order to reduce the sulfur content of the oils and otherwise to provide a product of improved quality.

Sulfur may exist in elemental as well as combined form in a variety of mineral oils, including both crude mineral oils and fractions thereof. By way of example, it may be mentioned that elemental sulfur has been heretofore observed in distillate fractions of petroleum oils. This sulfur has hitherto been considered to result largely from the oxidation of hydrogen sulfide dissolved in the fraction, rather than from the presence of elemental sulfur in the original crude oil from which the fraction was derived. However, recently completed investigations have shown that elemental sulfur may be present in certain crude petroleum oils. It is therefore possible that the sulfur found in distillate fractions has its origin in elemental sulfur contained in the crude oil. Although not all crude petroleum oils contain elemental sulfur, some crudes have been determined to contain more than one per cent by weight of elemental sulfur.

Elemental sulfur is highly undesirable in mineral oils, since it is highly corrosive to metals, as are combustion products of sulfur to a lesser degree. Also, elemental sulfur in oils acts as a source of malodorous and otherwise undesirable sulfur compounds, since it reacts readily with hydrocarbons present in mineral oils. It may be mentioned that hydrogen sulfide, one of the sulfur compounds resulting from the reaction of sulfur and hydrocarbons, is objectionable not only *per se*, but also in view of the fact that it may be easily reoxidized to the highly corrosive, elemental sulfur.

More specific difficulties resulting from the presence of elemental sulfur (or compounds derived therefrom) in crude or refined mineral oils are corrosion of pipe lines, of storage vessels, and of distillation and other refining facilities. Catalysts contacted by such oils during processing of the latter may lose activity at an accelerated rate. Sulfur-bearing lubricating oils or greases may lead to corrosion of lubricated bearing surfaces. Sulfur-bearing fuels, e. g., gasoline, kerosene and diesel oils, may exhibit a strong tendency toward haze and gum formation. Also, the lead-susceptibility of such gasolines is often low. The combustion products of such fuels may also lead to corrosion of metal surfaces contacted thereby.

Although aqueous solutions of alkali metal or alkaline earth polysulfides may be used in treating certain elemental sulfur-containing oils, such inorganic polysulfides are relatively inefficient as regards the extent of sulfur removal. In addition, use of such solutions, particularly those of relatively high concentrations, may lead to the formation of highly stable emulsions and/or foaming of the treated oils, and the serious difficulties attendant thereto.

It is a primary object of this invention to provide a simple and highly efficient process for refining mineral

2

oils containing objectionable amounts of sulfur determinable as elemental sulfur. Additional objects are to reduce maintenance costs, due to corrosion by sulfur and sulfur compounds, for pipe lines, storage facilities, and distillation and other refining equipment. Other objects are to reduce the corrosivity of, and to improve the odor, the stability, and the over-all quality of mineral oils which have been treated according to the herein disclosed invention. A detailed object of the invention is to provide a process of the kind indicated which will not lead to the formation of highly stable emulsions.

These and other objects are achieved by our invention which relates to a process for refining a mineral oil containing sulfur determinable as elemental sulfur. Briefly, the process includes the steps of contacting a mineral oil of this kind with an organic polysulfide which contains at least one linkage per molecule of the kind $—\text{S}_n—$, n being an integer of at least 2. After the contacting is completed, desulfurized oil is separated from the mixture under conditions at which the organic polysulfide and the oil are substantially immiscible.

Although the foregoing description is fully indicative of the nature of the invention to those skilled in the art, certain specific embodiments have been described in greater detail in the following amplification of the invention. It is understood that these embodiments are by way of illustration only and are not to be considered as limiting.

As indicated in the foregoing brief descriptions of the invention, the instant process is applicable to mineral oils which contain sulfur determinable as elemental sulfur. Such sulfur is determinable by the polarographic method, the procedure for which is described in detail in the article entitled "Elemental sulfur in crude oil" by Eccleston, Morrison and Smith appearing in the *Analytical Chemistry*, vol. 24, November 1952, at page 1745 et seq. Sulfur determinable as elemental sulfur by the polarographic method may include loosely combined sulfur which acts as elemental sulfur, as well as elemental sulfur itself. The invention, of course, includes treatment of mineral oils containing such combined sulfur, as well as elemental sulfur.

Thus, the process of this invention may be applied to sulfur-containing mineral oils of the above-identified type, whether crude or refined, and including not only crude petroleum oils and fractions thereof, such as gas oil, kerosene, naphtha, gasolines, LPG, topped crudes, fuel oils, lubricating oils, bright stock, and individual hydrocarbon oil constituents of the foregoing oils, e. g., benzene, heptane, decane and the like, but also sulfur-bearing oils obtained from the liquefaction of various coals, or oils obtained from the destructive distillation of coal or oil shale. The invention is especially important as applied to petroleum oils, since the normal usage of such oils renders malodorous and corrosive characteristics highly undesirable. The invention is of particular utility in treating sulfur-bearing, crude petroleum oils, since such oils normally contain greater concentrations of sulfur determinable as elemental sulfur than distillate oils derived therefrom. Accordingly, damage to equipment from such sulfur is potentially greatest in the instance of such oils.

As previously indicated, satisfactory treating materials for the purposes of this invention are organic polysulfides containing at least one $—\text{S}_n—$ linkage per molecule, where n is an integer of at least 2. Such polysulfides apparently combine with elemental sulfur through a mechanism not fully understood to form compounds or complexes corresponding to higher polysulfides, i. e., polysulfides having a greater number of sulfur atoms per molecule.

Taking up the polysulfide treating materials in more detail, it is essential for the purposes of this invention that

they be organic polysulfides. Although aqueous solutions of inorganic sulfides and polysulfides are capable of removing sulfur from petroleum oil, it has been found that organic polysulfides are distinctly superior to such inorganic polysulfides, especially insofar as completeness of elemental sulfur removal is concerned. Moreover, our organic polysulfides are normally used in substantially anhydrous form, thereby avoiding appreciable formation of highly stable emulsions.

It is also necessary for the purposes of this invention that the treating agent be a polysulfide, i. e., disulfides or higher polysulfides must be employed. The use of polysulfides is essential to this invention, since, unlike inorganic monosulfides, organic monosulfides exhibit little or no affinity for elemental sulfur at practical treating conditions. For this reason the active, elemental sulfur-absorbing $-\text{S}_n-$ linkages are those in which n is an integer of at least 2.

As has been indicated above, treating agents suitable for the purposes of this invention are those organic polysulfides which are substantially insoluble in or immiscible with the oil being treated at the conditions of separation. In addition, of course, the polysulfide-elemental sulfur product also should be mineral oil-insoluble under the same conditions. In general, the oil-solubility characteristics of polysulfides differing only in the number of sulfur atoms per molecule are substantially the same. This conveniences the separation of oil from unreacted and reacted treating material, since conditions at which the unreacted polysulfide is immiscible with the oil are also those at which the reacted polysulfide is immiscible with the oil.

Organic polysulfides which are substantially mineral oil-insoluble at atmospheric temperatures are distinctly preferred for economic reasons. However, the invention includes the use of polysulfides having appreciable mineral oil-solubility at the contacting conditions, so long as these polysulfides are substantially mineral oil-insoluble at the separation conditions. In such instances, it is necessary to adjust the conditions of separation in accordance with conventional principles to reduce the solubility or miscibility of the materials to the desired degree. Thus, the oil-solubility or miscibility of the materials may be reduced, for example, by reducing the temperature of the oil being treated, or by addition of an extraneous material to produce a sort of "salting out" of the polysulfide (and its addition product with sulfur) from the oil.

The property of oil-insolubility or immiscibility for the polysulfides is of great importance, since it is by virtue of this property that physical separation of the treated oil from the sulfur-bearing materials is effected. This separation distinguishes the subject invention from many sulfur-treating procedures which do not remove sulfurous components from the oil, but merely transform them.

Accordingly, suitable organic polysulfides are aliphatic or aromatic polysulfides or mixtures thereof, which exhibit a strong affinity for the type of sulfur indicated and which possess the above-described oil-solubility characteristics. Aliphatic polysulfides are usually preferred, since the oil-solubility of these compounds is more apt to be low. Polysulfides of the type included in the invention in general may be represented by the formula $\text{R}_1-\text{S}_n-\text{R}_2$, where R_1 and R_2 are organic radicals capable of imparting mineral oil-insolubility to the compound, and where n is at least 2. The organic radicals attached to the $-\text{S}_n-$ linkages may be aliphatic or aromatic and identical or dissimilar. They also may, and normally will, contain substituents, unsaturated linkages, and/or elements other than carbon and hydrogen, including nitrogen, halogens, sulfur, oxygen or phosphorous, which do not materially interfere with the sulfur-combining properties of the polysulfide linkage, and which do not impart appreciable oil-solubility to the over-all compound. Organic disulfides of the type indicated are especially advantageous, not only because of their greater

availability, relatively lower cost, and ease of reaction with elemental sulfur, but also because the disulfides possess greatest capacity for taking up elemental sulfur.

Specific examples of polysulfides which are suitable for the purposes of this invention are organic disulfides such as diacetyl disulfide, dithiodiglycol, i. e., bis-(β -hydroxyethyl) disulfide, or 2,2'-dithiodiethanol, formamidine disulfide, thiuram disulfide, tetramethylthiuram disulfide, bis-(α -amino propionic acid) disulfide (cystine) and esters thereof, especially lower alkyl esters, bis-(p -nitrophenyl) disulfide, dinitrobenzyl disulfide, dibenzoyl disulfide, alkyl dithiocarbamates, bis-(p -nitrophenoxythiophosphorus) disulfide; trisulfides such as bis-(p -tolyl) trisulfide; tetrasulfides corresponding to the di- and trisulfides mentioned above, and in addition, various proprietary polysulfide rubbers which are, in essence, polymeric tetrasulfides, e. g.,

Thiokol A ($\text{CH}_2\text{CH}_2-\text{S}_4-$) $_n$

20 Thiokol B ($\text{CH}_2\text{CH}_2-\text{OCH}_2\text{CH}_2-\text{S}_4-$) $_n$
Perduren H ($\text{CH}_2\text{CH}_2\text{O}-\text{CH}_2-\text{OCH}_2\text{CH}_2-\text{S}_4-$) $_n$

Vulcaplas ($\text{CH}_2\text{CH}-\text{CH}_2-\text{S}_4-$) $_n$

Particularly preferred are the bis-(alkanol) disulfides, and 25 especially those wherein the alkanol substituents contain five or less carbon atoms of which dithiodiglycol is representative.

The compounds listed above are representative of the 30 various classes of polysulfides which are effective treating agents in the process of this invention. Certain of the named compounds can be obtained commercially, as, for example, dithiodiglycol or the polysulfide rubbers; the remainder can be easily prepared by conventional methods.

35 In this connection, it is considered that the preparation of the various polysulfides disclosed need not be discussed in detail, since such preparation is entirely conventional, and since numerous such procedures have been disclosed in the literature. In the interest of clarity, 40 however, it will be briefly mentioned that organic polysulfides in general may be prepared by reaction of organic sulfates or halides with alkali metal polysulfides. Higher polysulfides may also be prepared by addition of elemental sulfur to lower polysulfides. Additionally, disulfides may be prepared by mild oxidation of mercaptans or thiophenols, including substituted members from each class. Trisulfides may be prepared by the reaction of thionylchloride or sulfonyl chloride with sulphydryl compounds. Tetrasulfides may be prepared by reacting sulfur chloride with mercaptans or thiophenols.

Our experimental work has shown that the organic polysulfides take up elemental sulfur extremely readily at ordinary, atmospheric temperatures and otherwise achieve a high degree of sulfur removal. Thus, usually 55 satisfactory processing temperatures are the normally encountered atmospheric temperatures, e. g., those between about 40° and about 100° F. Somewhat lower or higher temperatures can be used, if desired. Where sulfur removal tends to be sluggish or relatively incomplete, an improvement in results usually can be obtained by moderate heating of the oil-polysulfide mixture, e. g., to between about 100° and about 140° F., preferably in admixture with a small amount of a nitrogen-base catalyst, e. g., ammonia or a basic amine.

60 The treatment contact time and the oil:polysulfide ratio may vary quite widely, depending largely on the type of contacting procedure employed. Thus, it has been found that batch agitation of less than 5% by volume polysulfide with an oil containing substantial proportions of elemental sulfur for as little as five minutes was entirely adequate to effect substantially complete removal of elemental sulfur from the oil. The invention, of course, includes the use of shorter or longer contact times. Under certain conditions, as in the instance of an oil having a very high elemental sulfur con-

tent, or in the instance of an extremely low polysulfide:oil ratio, a somewhat longer contact time, e. g., up to say, 60 minutes or more, may be desirable.

Although low polysulfide:oil ratios have been found satisfactory, it is not necessarily implied that low ratios are always to be preferred. For example, in procedures involving a solid contact material, e. g., percolation of the sulfur-bearing oil through a particulate bed of polysulfide, or contact filtration utilizing a particulate material, the quantity of polysulfide contacted by a particular portion of oil may be quite large. The same would be generally true in instances of continuous oil desulfurization using liquid polysulfides, e. g., such as would result from the use of continuous liquid-liquid contacting means. However, it should be noted that from the standpoint of total oil contacted by polysulfide, the polysulfide:oil ratio in the instances noted above would be considerably lower.

As indicated in connection with the previous description of the invention, the polysulfide and oil are separated following the desulfurization treatment. In the instance of liquid polysulfides this may be accomplished by utilizing to advantage the immiscibility of the materials and the difference in their specific gravity. Thus, separation may be carried out in a batch-wise fashion, as by gravity settling, or continuously, as with centrifugal separators, or alternatively, as with time-settling tanks used in concurrent contacting, i. e., tanks of sufficient volume to provide the desired settling time while streams of separated materials are continuously withdrawn from the top and bottom of the tank, or the combination contacting and separating tanks used in liquid-liquid countercurrent contacting. Moderate heating of mixtures containing heavy oils may facilitate separation by reducing the viscosity of the oil. Where the solubility of the polysulfide is increased materially by heating, or in other instances, it may be preferred to reduce the viscosity of the oil by dilution. In the instance of relatively oil-soluble polysulfides for desulfurizing oils, the oil temperature is reduced during separation.

As is obvious, the step-wise addition of sulfur atoms to organic polysulfide molecules must ultimately result in the saturation of the latter with respect to elemental sulfur. At this stage, or at any more convenient previous stage of partial saturation, it may be desirable to effect regeneration of the saturated or partially saturated polysulfides to lower, less sulfur-saturated polysulfides. This may be accomplished by conventional methods; thus, for example, pentasulfides and tetrasulfides may be regenerated to trisulfides by distillation. Disulfides can be regenerated from trisulfides and higher polysulfides by acidification of the polysulfides to be regenerated (e. g., to a pH of about 6 or lower), and moderate heating, followed by extraction of the polysulfide with a hydrocarbon solvent or carbon disulfide to remove sulfur from the polysulfide. Alternatively, the extraction may be carried out with water, alcohols, glycols, ketones or the like to remove the polysulfide from the sulfur.

Although regeneration of the polysulfide may be desirable, it is not essential and may be dispensed with, if desired. In such instances, the exhausted polysulfide may be merely replaced with fresh polysulfide.

Although disulfides are preferred from the standpoint of sulfur capacity, trisulfides are preferred in regenerative processes, since they are more highly stable than other polysulfides. In such instances, the trisulfide may be sulfided to any desired degree and is then regenerated to the trisulfide form.

The principles of the subject invention may be utilized in producing and recovering elemental sulfur from mineral oils. In this modification, a mineral oil, e. g., a crude petroleum oil, is contacted with a suitable organic polysulfide, e. g., dithiodiglycol, and separation is effected as indicated above. After the desired degree of sulfur-saturation of the polysulfide has been reached, the poly-

sulfide-sulfur product is regenerated as described above, and elemental sulfur is separated therefrom by one of the extraction methods disclosed or other suitable separation procedure. The regenerated polysulfide is then recycled to the contacting step where it is again used to remove sulfur from fresh, sulfur-bearing oil.

Various advantages of the invention may be more easily understood by reference to the following specific examples:

Example I

Two hundred and fifty parts by volume of a McElroy (West Texas) crude petroleum oil containing sulfur determinable as elemental sulfur by the polarographic method was agitated with 60 parts by volume of dithiodiglycol for five minutes at room temperature, following which the mixture was allowed to settle. After separation of the mixture by decanting, the oil was analyzed for elemental sulfur. The extent of elemental sulfur removal obtained is indicated below:

	Before Treatment	After Treatment	Percent Elemental Sulfur Removed
Total Sulfur, Percent by Weight	2.45	1.99	
Elemental Sulfur, percent	0.443	0.0318	.93

The odor of the desulfurized oil was noted to have changed from foul to sweet following the treatment.

Example II

A large total capacity for elemental sulfur by organic polysulfides was determined by agitating 5 parts by volume of dithiodiglycol with a total of 125 parts by volume of the McElroy crude oil of Example I, in stages of 25 parts by volume each. It was determined that removal of elemental sulfur from the fifth sample was substantially as complete as from earlier samples. The degree of elemental sulfur removal obtained in the foregoing experiments from various samples is illustrated by the following tabulation:

	Crude Oil	Percent Elemental Sulfur
Original		0.443
First 25 parts aliquot		0.0361
Third 25 parts aliquot		0.0404
Fifth 25 parts aliquot		0.0410

At the end of the experiment the sulfur content of the dithiodiglycol was approximately 8% by weight. A still greater capacity for elemental sulfur is indicated by the fact that the portion of elemental sulfur absorbed by the dithiodiglycol in this experiment corresponds to less than one mol of added sulfur per mol dithiodiglycol. Accordingly, the theoretical capacity for elemental sulfur by the dithiodiglycol would be a multiple of that illustrated in the foregoing experiment.

Example III

The reduction of corrosivity of sulfur-bearing oils by our process was illustrated by subjecting a sample of a West Texas pipe-line crude oil having a total sulfur content of 1.47 and an elemental sulfur content of 0.0872% by weight before treatment and a sample of the McElroy crude employed in Example I respectively to extraction with approximately 25% by volume of dithiodiglycol for five minutes at room temperature. Each oil was subjected before and after treatment to the so-called "copper strip test" (ASTM-D-130-50T). These tests showed that the untreated crude oils were highly corrosive, while the treated crude oils produced no corrosion or tarnishing whatsoever.

The ASTM test D-130-50T is a conventional test, the

details of which are well-known to those skilled in the art. However, in order that the results indicated above may be easily evaluated, it may be mentioned briefly that the test involves immersion of a polished copper strip in a sample of the oil being tested followed by heating of the sample at a selected temperature and for a selected time characteristic of the material being tested. At the end of the test the copper strip is removed and compared with a reference strip. The tested strip is rated according to its appearance with a number 0, 1, 2, 3, 4 or 4+ for various degrees of corrosion. The foregoing numbers correspond respectively to no tarnish, slight tarnish, moderate tarnish, dark tarnish, slight corrosion and pronounced corrosion.

The copper strips employed in the testing of the samples mentioned above received the rating indicated in the tabulation below:

	McElroy Crude		West Texas Crude	
	Before Treatment	After Treatment	Before Treatment	After Treatment
ASTM D-130-50T, 3 hours, 122° F...	4+	0	4+	0

The results of this test indicate that the corrosion-causing materials in the oil have been effectively eliminated.

Example IV

The suitability of the present invention for removing elemental sulfur from low-boiling hydrocarbons was illustrated by agitating a benzene solution containing 1.3% elemental sulfur with approximately 25% by volume of dithiodiglycol for about five minutes and allowing settling to take place. The degree of desulfurization obtained is indicated in the results presented below:

	Benzene Before Treatment	Benzene After Treatment	Percent Elemental Sulfur Removed
Percent Elemental Sulfur.....	1.30	0.0618	95

Example V

A solution containing sodium polysulfide in a concentration calculated as about 17 grams Na₂S_{1.4} per liter was agitated with a sample of the McElroy crude oil utilized in Example I, using the same relative proportions of materials and the same contacting time as utilized in Example I. The degree of desulfurization obtained is indicated in the results presented below:

	Before Treatment	After Treatment	Percent Elemental Sulfur Removed
Percent Total Sulfur.....	2.44	2.08	67
Percent Elemental Sulfur.....	0.443	0.141	67

The percent sulfur determinable as elemental sulfur for the samples tested in each of the foregoing examples was determined by the Eccleston polarographic method, cited supra.

As indicated in the foregoing examples, treatment of elemental sulfur-containing mineral oils according to the process of this invention provides not only a material reduction in elemental sulfur content, but also an improvement in odor, and a reduction in corrosivity of the oil. As further shown, the use of organic polysulfides produces markedly superior results as compared with the use of inorganic polysulfides. It is to be understood that other organic polysulfides of the type disclosed herein can

be substituted for the organic polysulfide employed in the foregoing illustrative examples.

The invention is not limited to the use of any particular contacting apparatus. As indicated above, the desulfurization may be carried out by batch agitation of oil and polysulfide, or substantially continuously by percolation of the sulfur-bearing oil through a bed of particulate, solid polysulfide or liquid polysulfide supported on a particulate carrier, e. g., pumice, clay, or the like, or by liquid polysulfide extraction in any efficient liquid-liquid contacting apparatus, either of the concurrent or counter-current type. These and other commonly utilized contacting and separating systems may be employed with appropriate adaptation to the requirements of the particular materials utilized in this process. Such systems form no part of this invention and need not be described in detail. In passing, it is to be noted that small portions of polysulfide which remain in the oil following separation thereof may be removed, if desired, by solvent extraction of the oil with water or other oil-immiscible solvent for the polysulfide.

The above-described invention produces a distinct improvement in the quality of the oil products produced. Costs of maintenance due to corrosion by sulfur and sulfur compounds of distillation equipment, other refining equipment, and pipe line and storage facilities are reduced greatly by the use of the invention.

Numerous variations of the subject process may be resorted to without departing from the spirit of the invention. Accordingly, only such limitations should be imposed thereon as are indicated by the appended claims.

We claim:

1. A process of refining a mineral oil which contains sulfur determinable as elemental sulfur, comprising contacting said oil with an organic polysulfide desulfurizing agent that is normally substantially insoluble in said oil and which contains at least one linkage per molecule of the kind —S_n—, where n is an integer of at least 2, and then separating an oil phase of relatively reduced sulfur content that is substantially free from said desulfurizing agent from an oil-insoluble, organic polysulfide-containing phase of relatively increased sulfur content.
2. A process of refining a crude petroleum oil which contains sulfur determinable as elemental sulfur, comprising contacting said oil with an organic polysulfide desulfurizing agent that is normally substantially insoluble in said oil and which contains at least one linkage per molecule of the kind —S_n—, where n is an integer of at least 2, and then separating an oil phase of relatively reduced sulfur content that is substantially free from said desulfurizing agent from an oil-insoluble, organic polysulfide-containing phase of relatively increased sulfur content.
3. A process of refining a mineral oil which contains sulfur determinable as elemental sulfur, comprising contacting said oil with an aliphatic organic polysulfide desulfurizing agent which is normally substantially insoluble in said oil and which contains at least one linkage per molecule of the kind —S_n—, where n is 2, and then separating an oil phase of relatively reduced sulfur content that is substantially free from said desulfurizing agent from an oil-insoluble, organic polysulfide-containing phase of relatively increased sulfur content.
4. A process of refining a mineral oil which contains sulfur determinable as elemental sulfur, comprising contacting said oil with a bis-(alkanol) polysulfide desulfurizing agent which contains at least one linkage per molecule of the kind —S_n—, where n is 2, and which is normally substantially insoluble in said oil, and then separating an oil phase of relatively reduced sulfur content that is substantially free from said desulfurizing agent from an oil-insoluble, organic polysulfide-containing phase of relatively increased sulfur content.
5. A process of refining a mineral oil which contains sulfur determinable as elemental sulfur, comprising con-

5. A process of refining a mineral oil which contains sulfur determinable as elemental sulfur, comprising con-

tacting said oil with dithiodiglycol, and then separating an oil phase of relatively reduced sulfur content from an oil-insoluble phase.

6. A process of refining a crude petroleum oil containing sulfur determinable as elemental sulfur, comprising contacting said oil with dithiodiglycol, and then separating an oil phase of relatively reduced sulfur content from an oil-insoluble phase.

7. A process of refining a mineral oil which contains sulfur determinable as elemental sulfur, comprising contacting said oil with an organic trisulfide desulfurizing agent that is normally substantially insoluble in said oil and which contains at least one linkage per molecule of the kind $-S_n-$, where n is 3, separating an oil phase of relatively reduced sulfur content that is substantially free from said desulfurizing agent from an oil-insoluble, organic polysulfide-containing phase of relatively increased sulfur content, subjecting sulfur-enriched material obtained from said separating to a regenerative treatment to liberate elemental sulfur and said trisulfide, separating the sulfur from the trisulfide and again contacting addi-

tional mineral oil with the recovered trisulfide as described.

8. A method of refining a mineral oil and recovering elemental sulfur from mineral oil containing sulfur determinable as elemental sulfur comprising contacting said oil with an organic polysulfide desulfurizing agent that is normally substantially insoluble in said oil and which contains at least one linkage per molecule of the kind $-S_n-$, where n is an integer of at least 2, separating an oil phase of relatively reduced sulfur content that is substantially free from said desulfurizing agent from an oil-insoluble, organic polysulfide-containing phase of relatively increased sulfur content, subjecting sulfur-enriched material obtained from said separating to a regenerative treatment to liberate elemental sulfur, and then separating the thus liberated elemental sulfur.
